(57) **CLAIM**

The ornamental design for a twist pet chew, as shown.

DESCRIPTION

FIG. 1 is a perspective view of a twist pet chew of the present invention;

FIG. 2 is a front end view of the twist pet chew of FIG. 1;

FIG. 3 is a back end view of the twist pet chew of FIG. 1;

FIG. 4 is a top view of the twist pet chew of FIG. 1;

FIG. 5 is a bottom view of the twist pet chew of FIG. 1;

FIG. 6 is a left side view of the twist pet chew of FIG. 1; and,

FIG. 7 is a right side view of the twist pet chew of FIG. 1.

The broken lines in FIGS. 1–3 illustrate portions of the pet treat which form no part of the claimed design.
